CAKE PLATE

Albert A. Surina, North Plainfield, N. J.

Application August 21, 1948, Serial No. 148,232

Term of patent 7 years

(Cl. D44—19)

To all whom it may concern:

Be it known that I, Albert A. Surina, a citizen of the United States; residing at 142 DeLacy Street, in the Borough of North Plainfield, in the county of Somerset and State of New Jersey, have invented a new, original, and ornamental Design for a Cake Plate, of which the following is a specification, reference being had to the accompanying drawing, forming part thereof.

I claim:

The ornamental design for a cake plate, substantially as shown.

ALBERT A. SURINA.
